UNITED STATES PATENT OFFICE

FRANK W. ROLLER, OF EAST ORANGE, NEW JERSEY, ASSIGNOR TO ROLLER-SMITH COMPANY, A CORPORATION OF NEW YORK

RAIL BOND TESTER

Application filed March 8, 1926. Serial No. 93,039.

This invention relates to rail bond testers which include electric testing instruments, the circuits of which are energized by current derived from the rail through rail engaging contacts carried by a contact bar or similar device.

When the rails are normally carrying current as from cars operating on track, this current may be utilized for energizing the testing circuits and making the tests. This, however, is impossible if the rails do not happen to be carrying current at the time it is desired to make the test and one object of the present invention is to provide a convenient means for establishing a flow of current through the rails in such cases. For this purpose, I provide additional rail engaging contacts on the contact bar, a suitable source of current such as a small battery or dry cell carried by the contact bar and connections between said source and contacts, the parts being so arranged that when the contact bar is pressed against the rail so as to connect the testing circuits with the rail, the additional contacts also engage the rail so that current from the source will be supplied to the rail; this current being utilized to energize the circuits of the testing apparatus. To avoid closing the circuit through the battery at the times when the rails are carrying current, and current from the battery is, therefore, unnecessary, I provide a switch in the connections between the source and additional contacts, and in the preferred embodiment of my invention, this switch is normally open, and may or may not be closed by the operator's foot in pressing the contact bar against the rail.

A further object in my invention is to provide an improved contact bar embodying the instrumentalities above mentioned which bar is of simple and light construction, is collapsible so as to facilitate carrying, and which, at the same time, is strong and durable and efficient in use.

A further object of my invention is to provide improved rail-engaging contacts which are so constructed and mounted as to insure engagement of all of the contacts with the rail when the contact bar is pressed against the

rail, so that a good electrical connection is formed between each of the contacts and the rail.

Further objects and advantages of my invention will appear from the following description taken in connection with the accompanying drawings, wherein

Fig. 1 is a side elevation of a rail and contact bar applied thereto, together with a conventional showing of the electrical circuits of the testing apparatus including a testing rheostat and galvanometer; Fig. 2 is a sectional view taken on the line 2-2 of Fig. 1; Fig. 3 is a side elevation of the contact bar folded; Fig. 4 is an enlarged view of one end of the contact part partly in longitudinal section and partly in elevation showing in detail two of the rail engaging contacts; and Fig. 5 is an enlarged elevation of one end of the contact bar.

Referring to Fig. 1, 10 and 11 represent two track rails joined together by a rail bond 12. 14 represents a contact bar which comprises a handle 15 to the lower end of which are secured plates 16 between which are pivoted members 19 and 20, which in their operative or rail engaging position extend outwardly from the handle 15 and are held in such position by braces 23 and 24. These braces are pivotally secured at one end to the handle 15, and are detachably secured at the other end to the members 19 and 20 respectively. When the braces are detached from the parts 19 and 20, these parts may be folded up against the handle as shown in Fig. 3 for convenient carrying of the bar when not in use.

In the embodiment of the invention herein disclosed, the contact bar carries three rail engaging contacts, namely, contacts 25 and 26 carried by the parts 19 and 20, respectively, and contact 27 carried by the lower end of the handle 15; these three contacts forming parts of the testing circuits; and the contact bar also carries two additional contacts 28 and 29 located respectively at the outer ends of the parts 19 and 20, these additional contacts forming part of the circuit for supplying current to the rail.

Contacts 25, 26 and 27 are of similar form and each is rigidly secured to the part of the

bar on which it is mounted. Figs. 4 and 5 show the form of one of these contacts, namely contact 25 on part 19. It comprises a metal body portion 30, which embraces and is suitably secured to the part 19 of the contact bar and which is formed with downwardly inclined arms 31 having slots 32 adapted to receive rail engaging members 33, which, in the preferred construction are sections of a hack-saw. Members 33 are removably held in the slots 32 by screws 35 and members 33 are so positioned that when the contact bar is pressed downwardly against the rail, the saw teeth engage two top edges of the rail, and serve to penetrate any scale or non-conducting coating on the surface of the rail and form a good electrical contact with the metal of the rail. Fig. 2 shows the center contact 27 engaging the rail in this manner. The body portion 30 of the contact carries a binding post 36 for connection thereto of a conducting lead.

Contacts 28 and 29 have rail engaging saw blades carried by downwardly inclined arms 37 of a body portion 38, and the saw blades are positioned relatively to one another similarly to the saw blades on the contacts 25, 26 and 27. Contacts 28 and 29 are supported so that they may yield relatively to the parts 19 and 20 respectively. The mounting of the contact 28 is shown in Fig. 4. A spring 40 carried in a tube 41 in part 19 presses against the upper end of the body portion 38, normally holding the body portion 38 against a supporting bracket 42, which is secured to the part 19 and extends beneath the body portion 38 between the projecting arms 37. When the contact bar 14 is pressed against the rail and the saw teeth of the contacts 28 and 29 engage the top edges of the rail, and the yieldable connections between these contacts and part 19 and 20 permit the bar to move toward the rail until contacts 25, 26 and 27 come into firm engagement with the rail. Inasmuch as contacts 25, 26 and 27 are spaced some distance apart and the contact bar itself is somewhat resilient, a pressure applied to the part 19 or 20 of the bar somewhat near their connection with the handle will force all three contacts, 25, 26 and 27 into engagement with the rail.

50 represents a portable box or case which contains a rheostat 51 and a galvanometer 52. The rheostat 51 comprises a resistance 54, one terminal 55 of which is connected to the contact 26 by flexible conductor 56 and the other terminal 57 of which is connected to the contact 25 by a flexible conductor 58. Movable over the resistance 54 is a contact arm 60 which may be turned by a knob 61, so as to form contact with the resistance 54 at any point along its length, and a pointer 62 movable with the arm 60 cooperates with a dial 63 to indicate the position of the arm 60 on the resistance 54. The contact arm 60

is connected through a galvanometer 52 to the center contact 27 of the contact bar by means of a flexible conductor 65.

70 represents a battery or dry cell which is carried in any convenient manner by the handle 15 of the contact bar. As shown, the battery 70 is supported by a bracket 71 secured to the handle 15 and a strap 72 which encircles the battery and handle, holds the latter firmly against the handle. One terminal of the battery is connected by means of a conductor 74 to the contact 29 and the remaining terminal of the battery leads through a conductor 76 to a push switch 75, mounted in the part 19 of the contact bar. A conductor 77 leads from the rail engaging contact 28 to the push switch 75, and conductors 76 and 77 are adapted to be electrically connected by a movable switch contact member 79, which is normally held in an upper or circuit open position by a spring 80 contained in a tube 81 in the part 19 and engaging a collar 82 formed on the contact member 79. Contact member 79 extends upwardly a slight distance above the top of the part 19 where it may be engaged by the foot of the operator in pressing the contact bar against the rails.

To test the rail bond by the apparatus described, the bar is placed along the rail so that contacts 26 and 27 are at opposite sides of the bond to be tested. As it is unnecessary to use the battery current when the rails are already carrying current, the bar will be first pressed against the rails in such a manner as not to close the switch 75. This may be done by pressing the foot against the inner end of the part 20 of the contact bar, and in case current is flowing through the rails this will be indicated by a movement by the galvanometer needle. If the galvanometer does not indicate a flow of current through the rails, the operator will place his foot over the switch 75 and press the bar against the rails thereby simultaneously closing the switch. In this manner there will be applied to the rails between the contacts 28 and 29 a difference of potential necessary to make the test. When the bar has been pressed against the rails as above described and the galvanometer has indicated a current flow through the rails, the arm 60 will be adjusted along the resistance 54 until the galvanometer gives a zero deflection. The circuits now established form a Wheatstone bridge with the resistances of the arms of the bridge so adjusted that no current is flowing through the bridge circuit. The arms of the bridge at one end of the bridge or galvanometer circuit are the resistance of the rail bond 12, and the resistance of a length of track equal to the distance between the contacts 25 and 27. The other two arms of the bridge are formed by the portions of the resistance 54 at opposite sides of the arm 60.

If the ratio of the resistances of these two portions of the resistance 54 are known, the resistance of the bond 12 in terms of the resistance of the standard length of rail, that is, the length equal to the distance between the contacts 25 and 27 may be ascertained. Dial 63 will ordinarily be graduated, to read directly in ratio of bond resistance to resistance of standard length of rail.

10 Although one specific embodiment of my invention has been shown and described, various modifications may be made without departing from the scope of this invention.

I claim:

15 1. In an apparatus for testing the electric resistance of rail bonds, a contact bar arranged to be held pressed against the rail by foot pressure, an electrical measuring instrument, a pair of spaced testing contact members disposed on said bar so as to be brought into engagement with the rail on application of foot pressure to said bar, circuit connections between said testing instrument and said testing contact members whereby upon 20 application of foot pressure to said bar, said testing contact members will be brought into engagement with said rail and cause rail return current flowing through said rail to produce on said instrument an indication of the 25 resistance of a tested rail section between said testing contact members, a pair of auxiliary contact members disposed on said bar outside said spaced testing contact members, an auxiliary current source associated with 30 said apparatus, a normally open switch disposed on said bar arranged to be closed upon application of foot pressure to a predetermined portion of said bar, and connections between said auxiliary contact members, said auxiliary source, and said switch arranged so that upon application of foot pressure to said bar, said switch will be closed, causing a flow of current from said auxiliary source through said rail to produce on said instrument an indication of the resistance of the aforesaid tested rail section in the same terms as when actuating said instrument with rail return current, said auxiliary contact members being relatively yieldably mounted on said bar compared to said testing contact members so that upon application of foot pressure to said bar, said auxiliary contact members will yield until said testing contact members have been brought into engagement with the rail to be tested.

35 2. An apparatus for testing the electrical resistance of rail bonds, a contact bar adapted to be held pressed against the rail by foot pressure, an electrical measuring instrument, a pair of outer testing contact members and an intermediate testing contact member disposed on said bar so as to be brought into engagement with the rail upon application of foot pressure to said bar, circuit connections 40 between said testing instrument and said testing contact members arranged so that upon application of foot pressure to said bar, said testing contact members will be brought into engagement with said rail and cause rail return current to produce on said instrument an indication of the resistance of a tested rail section between the intermediate testing contact member and one outer testing member in terms of the resistance of a standard rail section, a pair of auxiliary contact members disposed on said bar outside said outer testing contact members, an auxiliary current source associated with said apparatus, a normally 45 open switch disposed on said bar so as to be closed upon application of foot pressure to a predetermined portion of said bar, and connections between said auxiliary contact members, said auxiliary source, and said switch, arranged so that upon application of foot pressure to said predetermined portion of said bar, said testing and auxiliary testing contact members will be brought into engagement with said rail and simultaneously said switch

turn current flowing through said rail to produce on said instrument an indication of the resistance of a tested rail section between said testing contact members, a pair of auxiliary contact members disposed on said bar outside said spaced testing contact members, an auxiliary current source associated with said apparatus, a normally open switch disposed on said bar arranged to be closed upon application of foot pressure to a predetermined portion of said bar, and connections between said auxiliary contact members, said auxiliary source, and said switch arranged so that upon application of foot pressure to said predetermined portion of said bar, said testing and auxiliary contact members will be brought into engagement with said rail and simultaneously said switch will be closed, causing a flow of current from said auxiliary source through said rail to produce on said instrument an indication of the resistance of the aforesaid tested rail section in the same terms as when actuating said instrument with rail return current, said auxiliary contact members being relatively yieldably mounted on said bar compared to said testing contact members so that upon application of foot pressure to said bar, said auxiliary contact members will yield until said testing contact members have been brought into engagement with the rail to be tested.

50 3. An apparatus for testing the electrical resistance of rail bonds, a contact bar adapted to be held pressed against the rail by foot pressure, an electrical measuring instrument, a pair of outer testing contact members and an intermediate testing contact member disposed on said bar so as to be brought into engagement with the rail upon application of foot pressure to said bar, circuit connections between said testing instrument and said testing contact members arranged so that upon application of foot pressure to said bar, said testing contact members will be brought into engagement with said rail and cause rail return current to produce on said instrument an indication of the resistance of a tested rail section between the intermediate testing contact member and one outer testing member in terms of the resistance of a standard rail section, a pair of auxiliary contact members disposed on said bar outside said outer testing contact members, an auxiliary current source associated with said apparatus, a normally 55 open switch disposed on said bar so as to be closed upon application of foot pressure to a predetermined portion of said bar, and connections between said auxiliary contact members, said auxiliary source, and said switch, arranged so that upon application of foot pressure to said predetermined portion of said bar, said testing and auxiliary testing contact members will be brought into engagement with said rail and simultaneously said switch

will be closed, causing a flow of current from said auxiliary source through said rail to produce on said instrument an indication of the resistance of the tested rail section in the same terms as when actuating said instrument with rail return current.
